UNITED STATES PATENT OFFICE.

WILLIAM J. TRUMPOUR, OF CHICAGO, ILLINOIS, AND WENCHEL WIRTH, OF ST. JOSEPH, MICHIGAN; SAID WIRTH ASSIGNOR TO SAID TRUMPOUR.

JACK.

1,416,912.

Specification of Letters Patent. Patented May 23, 1922.

Application filed December 19, 1919. Serial No. 346,129.

To all whom it may concern:

Be it known that we, WILLIAM J. TRUMPOUR and WENCHEL WIRTH, citizens of the United States, residing at Chicago, in the county of Cook and State of Illinois, and St. Joseph, in the county of Berrien and State of Michigan, respectively, have invented certain new and useful Improvements in Jacks, of which the following is a specification.

10 The invention relates to lifting jacks such as are employed in lifting automobiles and the like, and has for its general aim the provision of a jack which can be conveniently operated from a point removed a substantial 15 distance from the jack.

The general object of the invention is to provide a jack of a very practical character in that it is simple in construction and positive in operation.

20 An important object of the invention is to provide a jack which may be operated with an extremely short stroke of the operating lever from an initial horizontal position to an uppermost position at a minimum degree of inclination.

25 A further object of the invention is to provide reversing mechanism which may be readily manipulated by means of an extension operating handle.

30 A further object of the invention is to provide an improved construction for the operating handle.

The objects of the invention thus generally stated, together with other and ancillary 35 advantages, may be attained by the construction and arrangement illustrated in the accompanying drawings forming part hereof in which, Figure 1 is a side elevation of a jack embodying the features of our invention. Fig. 2 is a horizontal section through the jack taken on line 2-2 of Fig. 1. Fig. 3 is a fragmentary vertical section through the operating mechanism of the jack. Fig. 4 is a perspective view of the reversing member. Fig. 5 is a fragmentary side elevation of the extension operating handle.

40 The jack comprises generally a standard 1, a bar 2 provided with rack teeth 3, a pinion 4 meshing with the rack bar, a ratchet wheel 5 rigid with said pinion, and an operating lever 6 having an actuating member 7 therein adapted to engage operatively with the ratchet wheel. 8 designates a holding

dog adapted to coact with the ratchet wheel 55 and 9 is a reversing member.

The standard 1 having a supporting base 10, is made hollow to receive the rack bar 2, and its upper portion is enlarged as at 11 forming a housing to receive the actuating 60 mechanism and having an opening 11^a in its forward wall. The rack bar 2 may if desired, carry a step 12 of usual construction.

65 The rack bar 2 may be guided by the standard 1 for vertical movement in any suitable or preferred manner; and the pinion 4 meshing with the rack teeth 3 of the rack bar, together with the ratchet wheel 5, is mounted on a pivot pin 13 carried by the 70 housing 11.

75 The operating lever 6 is forked at its forward end to provide arms 14 and 15 adapted to receive neatly between them the pinion 4 and ratchet wheel 5, the said arms being also pivotally mounted on the pivot pin 13. The space between the arms 14 and 15 is reduced at their junction to neatly receive the actuating member 7 (Fig. 2), which is aligned with the ratchet wheel 5 for operative engagement therewith.

80 The actuating member 7 is mounted on a pivot 16 (Fig. 2) and has upper and lower fingers 7^a and 7^b and a rearwardly extending arm 17. A controlling spring 85 18 entered in a socket 19 formed in the handle bears against said arm 17 and tends to force the arm 17 to one side or the other of dead center so as to hold either the finger 7^a or the finger 7^b in operative engagement with the ratchet wheel 5. Normally the lower finger 7^b is held by the spring 18 in engagement with the ratchet wheel 5.

90 The holding member 8 is mounted on a pin 19 carried by the housing 11 and has a 95 downwardly extending finger 20 which is normally held in engagement with the teeth of the ratchet wheel 5 by means of a spring 21. The ratchet wheel 5 is made of a diameter substantially greater than the pinion 100 4 and with a substantially greater number of teeth, and the parts are so arranged that upon an up-and-down movement of the lever 6, the ratchet wheel is rotated one tooth at a time, the member 8 serving to hold the 105 rack bar against descent during the upward movement of the lever. It will be seen that by the use of a ratchet wheel having a rela-

tively greater number of teeth than the pinion 4, the length of stroke of the operating lever is reduced to a minimum. This is advantageous in the operation of the jack 5 in that the tendency of the operating handle to strike parts of the vehicle which is being raised or lowered is substantially reduced.

The reversing device comprises a flat member or plate 9 which is entered between one arm of the operating lever 6 and the adjacent wall of the housing, and is mounted upon the pivot pin 13. For receiving the pin 13, the plate 9 is provided with an elongated opening 22, and for guiding the plate for movement longitudinally of the operating lever, the plate has a slot 23 adapted to receive a guide stud 24 projecting from the side of the lever 6; and as an additional guiding means the lever is provided with a stud 22^a for coacting with the opening 22 in the member 9. Upon its upper inner edge the plate 9 carries a cam member 25 in the form of a coiled spring which serves to control the movements of the holding member 8. To this end, the cam member 25 is arranged to engage with the holding member 8, when the member is moved to its outermost position as determined by the pin 13 engaging with the forward or inner end of the elongated opening 22. Thus, referring to Fig. 3 (dotted lines), it will be seen that when the reversing device is in its outermost position, the cam member 25 serves to hold the holding member 8 out of engagement with the teeth of the ratchet wheel 5 until the lever 6 approaches the limit of its upward movement, whereupon the finger 20 of the holding member is permitted to engage with the ratchet wheel. In this operation, the holding member is controlled by the cam member 25, which, as the lever moves upwardly, moves inwardly away from the holding member; and by the time the finger engages with the ratchet wheel it has escaped past one of the teeth thereof to permit a gradual lowering of the rack bar.

In order to effect such downward movement of the rack bar, it also becomes necessary for the finger 7^b of the actuating member to escape past a tooth of the ratchet wheel in the downward movement of the lever. This is effected by a reversal of the position of the actuating member against the action of its controlling spring 18, and for this purpose a cross pin 27 is carried by the housing in position to be engaged by the finger 7^a of the actuating member when the lever 6 is swung to its uppermost position. After such reversal of the position of the actuating member, the member is again moved into its position upon completion of the downward stroke of the lever by reason of the cam engagement of the finger

7^b with the lower edge of the opening 11^a in the forward wall of the housing. When thus moved into its normal position, the actuating member engages with the ratchet wheel to lock it against rotation relative to the lever, so that in the upward movement of the lever, the rack bar descends until the finger 20 of the holding member engages the ratchet wheel preventing a further downward movement of the rack bar until the lever is again swung upwardly and the actuating member again reversed.

To prevent an accidental movement of the reversing device, the opening 22 in the member 9 is provided in its upper edge 80 with a pair of notches 28 and 29 adapted to receive the pin 13; and the spring cam member 25 is adapted to bear upon the holding member so as to yieldingly hold the member 9 downwardly with the pin engaging 85 in either one of said notches.

For the purpose of preventing a reversal of the position of the actuating member 7 by reason of the movement of the hand lever upwardly to such an extent that the finger 7^a of the actuating member engages the pin 27 in the housing to shift it, we have provided a stop 30 on the reversing device. This stop may be in the form of an integral lug, and is adapted when the reversing device is in its innermost or elevating position to engage with a stop-shoulder 31 (Fig. 1) provided in the adjacent wall of the housing 11. It will be understood that when the reversing device is moved outwardly to the reversing position that the stop 30 is moved therewith so as to clear the stop-shoulder 31 on the housing whereby to permit the upward movement of the hand lever sufficiently to effect a shifting 105 of the actuating member.

When the reversing device is in its outer or operative position, the actuating dog may be manually controlled to permit of a free movement of the rack bar. In such position 110 of the reversing device, the finger 20 of the holding member 8 is, it will be remembered, held by the spring cam member 25 out of engagement with the ratchet wheel 5. Accordingly, if the operator by means of his 115 thumb and forefinger moves the actuating member 7 into a neutral position so that neither of the fingers 7^a or 7^b engages with the ratchet wheel, the rack bar, it will be apparent, is released.

In order that the jack may be manipulated from a point removed therefrom a substantial distance, we provide on the member 9 of the reversing device an operating stud 32 with which the hooked end of an extension handle 33 may engage. Referring to Fig. 5, the handle preferably comprises two sections 33^a and 33^b arranged to be secured together either in extended or collapsed form. The section 33^a is provided 130

with a hook 34 suitably formed in the extreme end thereof, and said end is adapted to be inserted in the usual socket of the operating handle. The hook is so shaped as 5 to provide a shoulder 35 for engagement with the operating stud 32 of the reversing device to move it inwardly. Herein the means for connecting the two sections together comprises a bolt 36 carried by the 10 section 33^b and entered through a slot 37 in the opposite section, with a wing-nut 38 for locking the two sections together. A headed stud 39 is also carried by the section 33^a and is arranged to enter a bayonet slot 15 40 and locked in position therein by the wing-nut 38.

We claim as our invention:

1. A jack comprising, in combination, with a standard having a rack bar mounted 20 for vertical movement therein, a pinion pivotally mounted relative to the standard and meshing with the rack bar, a ratchet wheel of greater diameter than the pinion and rigid therewith, an operating handle pivoted co-axially with said pinion and having an actuating member for operatively engaging said ratchet, and a holding member engaging said ratchet for preventing rotation of the pinion.
2. A jack comprising, in combination 30 with a standard having a rack bar mounted for vertical movement therein, a pinion pivotally mounted relative to the standard and meshing with the rack bar, a ratchet wheel of greater diameter than the pinion and rigid therewith, an operating handle pivoted co-axially with said pinion and having an actuating member for operating the same, and a holding member for said rack 40 bar adapted to coact with said ratchet wheel.
3. A jack comprising, in combination with a standard having a rack bar mounted for vertical movement therein, a pinion pivotally mounted relative to the standard and meshing with the rack bar, a ratchet wheel of greater diameter than the pinion and rigid therewith, an operating handle pivoted co-axially with said pinion and having an actuating member for operating the same, 50 a holding member adapted to coact with said ratchet wheel, and means mounted upon the operating lever for controlling the holding member.
4. In a jack, the combination of a rack 55 bar, a pinion meshing with the rack bar, a toothed wheel rigid with the pinion, an operating lever having an actuating member for operatively engaging said toothed wheel, a holding member also adapted to engage with said toothed wheel, and a cam member 60 carried by the operating lever and movable relative thereto to control the position of said holding member.
5. In a jack, the combination of a rack 65 bar, a pinion meshing with the rack bar, a

toothed wheel rigid with and of greater diameter than the pinion, an operating lever having an actuating member, a holding member coacting with said toothed wheel to prevent movement of the rack bar, means operatively associated with the operating lever for controlling the position of the holding member, and means for controlling the position of the actuating member operable in the movements of the lever.

6. In a jack, the combination of a rack bar, a pinion meshing with the rack bar, a toothed wheel rigid with the pinion, means operatively engaging the toothed wheel to rotate it step by step, a holding member for 70 the rack bar, and a reversing device operatively associated with the holding member and the actuating means, said device comprising means adapted in its inoperative position to maintain the same normally so.

7. In a jack, the combination of a rack bar, a pinion meshing therewith, a toothed wheel rigid with said pinion, means operatively engaging the toothed wheel to rotate it step by step, a holding member for 80 the rack bar, and a reversing device operatively associated with the holding member and the actuating means, said reversing device comprising a member pivoted coaxially of said pinion but shiftable relative thereto and having a cam member adapted to engage with the holding member to control its position.

8. In a jack, the combination of a rack bar, a pinion meshing with the rack bar to move it, a toothed wheel rigid with the 100 pinion, a hand lever having an actuating member for engaging with the toothed wheel, a holding member also adapted to engage with the toothed wheel, a reversing device carried by the lever and having a cam portion movable into engagement with the holding member to move it out of engagement with the toothed wheel in one position of the lever, but permitting such engagement in another position of the actuating lever.

9. In a jack, the combination of a rack bar, a pinion meshing with the rack bar, a holding member for the rack bar, means including an actuating lever for rotating 115 said pinion, and a reversing device operable in the movement of the lever to control the movement of the holding member, said device comprising means operable when the same is in inoperative position to maintain 120 the same normally in this relation.

10. In a jack, the combination with a rack bar and a pinion meshing therewith, of a holding member for the rack bar, means for rotating the pinion comprising an operating lever, an actuating member carried by the operating lever, means with which the actuating member is adapted to engage in the movement of the lever in effecting a reversal of the jack, a reversing device 130

mounted for movement with the operating lever and adapted to engage the holding member, and means carried by the reversing device adapted in the inoperative position 5 thereof to prevent a shifting of the actuating member in the movement of the lever.

11. In a jack, the combination with a rack bar and a pinion meshing with the rack bar, of a holding member for the rack bar, an 10 operating lever having an actuating member, means arranged for shifting the actuating member in the operation of the handle to effect a reversal of the jack, a reversing device comprising a member mounted for 15 movement longitudinally of the lever and having a part arranged to engage the holding member, and means for limiting the upward movement of the operating lever to prevent a shifting of the actuating member 20 when the reversing device is in its inoperative position.

12. In a jack, the combination of a rack bar, a pinion meshing with the rack bar, a holding member for the rack bar, a lever 25 operatively associated with the pinion, means for controlling the holding member including a movable member, and a handle adapted to engage either with the operating lever or with said movable member to actuate it.

13. In a jack, the combination with a rack bar and a pinion meshing therewith, of a toothed wheel rigid with the pinion, a holding member for the rack bar, an operating 30

lever having an actuating member adapted 35 to engage with the toothed wheel, and a reversing device carried by the actuating lever and adapted to engage with the holding member to control the position thereof, said reversing device having a part adapted for 40 engagement by a hooked handle for operation thereby from a point removed a substantial distance from the jack.

14. The combination with a jack having an operating lever provided with a socket, 45 and a reversing device carried by the operating lever and movable longitudinally thereof to effect a reversal of the jack, of a handle adapted to engage in the lever socket and provided with a hooked portion for engaging 50 with the reversing device to operate it.

15. In a jack, the combination with a rack bar and a pinion mounted on a pivot and meshing with the rack bar, of an operating lever having an actuating member operatively associated with the pinion, a reversing device comprising a plate having an elongated opening for receiving said pivot, said opening having a pair of notches in which said pivot is adapted to engage, and a spring 55 member carried by said plate adapted to engage with the holding member and tending to hold said plate in position with the pivot engaging in either one of said notches.

In testimony whereof we have hereunto 65 set our hands.

WILLIAM J. TRUMPOUR.
WENCHEL WIRTH.
